DOFFING A WINDING MACHINE

Paul W. Markwood, Lowland, John T. Rich, Morristown, and Paul D. Lingerfelt, Lowland, Tenn., and Charles F. Nichols, Waynesville, N. C., assignors to American Enka Corporation, Enka, N. C., a corporation of Delaware

Application September 10, 1953, Serial No. 379,397

4 Claims. (Cl. 242—35.5)

This invention relates to the doffing and threading-in of winding machines and more particularly to the threading-in of cone winding machines with large numbers of runnings ends.

In the more modern continuous spinning systems, large numbers of finished yarns are dried simultaneously in warps of great width. These continuously running ends are required to be collected in some manner and all collective devices, regardless of type, have to be doffed from time to time. Doffing a collecting device which is being supplied by a continuously running end is always difficult, for it inherently involves the problems of taking up the running end after it is severed from the wound body and the initiation of the formation of a new wound body. These problems are, of course, aggravated where the permissible number of knots is related to sale value and where the number of running ends to be handled is large.

It is therefore an object of this invention to provide for the facilitated threading-in of a winding machine with a running end of yarn.

It is proposed according to this invention to thread-in serially a large number of winding machines served by a single warp of running ends and to do so with low cost in operator time, low waste of yarn and low knot production while preserving the plant in a neat and clean condition.

Other objects and advantages of this invention will be apparent from the following detailed discussion of an embodiment thereof in conjunction with the annexed drawings wherein:

Figure 1 is a view in side elevation of a coning machine and an ambulant waste and finished cone receiving device both modified according to the present invention;

Figure 2 is a front view of the coning machine of Figure 1;

Figure 3 is a view in elevation of the ambulant device of Figure 1 taken from a position 90° removed from the view point of Figure 1;

Figure 4 is a view in section taken on the line 4—4 of Figure 3;

Figure 5 is a top plan view of a typical plant arrangement according to the present invention; and

Figure 6 is an enlarged view in side elevation of the suction device and thread guide shown in Figure 1.

Referring now to the drawings in greater detail, it will be noted that there is shown, in Figures 1 and 2, a basically conventional cone winding machine equipped with certain accessory mechanisms according to the present invention. It is also to be understood that the coning machine shown is typical of a large number of such machines which are used simultaneously, one coning machine serving each yarn of the total warp delivered by the spinning machine. For convenience of illustration, the threading-in operation will be described with respect to but a single unit, the arrangement of the units being shown in the block diagram which constitutes Figure 5.

The machine of Figure 2 includes the usual elements of a cone winder such as a pivoted traverse frame 10 and

a spindle 11 adapted to receive thereover a cardboard cone on which the conical yarn body is wound. Yarn to be wound passes from the source over a guide roller 12 under a dancer roller 13 and up to the traverse button 14 which lays it up on the cone. The equipment as thus far described is disclosed for information purposes and constitutes no part of the present invention. On the coning machine, as depicted in Figures 1 and 2, there is mounted a suction device 15 which is generally of the design shown in application Serial No. 237,526, filed July 19, 1951, now Patent No. 2,661,588 issued December 8, 1953, and owned by the owner of the present application. The suction device in essence, consists of a cylindrical body having a notch therein and a jet mechanism at the base of the notch whereby thread dropped in the notch will be jetted out of the device onto any suitable target. In the present case the jet discharges through a tube 16 while it is fed through a tube 17 having a valve 18 therein. The tube 17 extends from a manifold 19 which provides compressed air not only for the tube 17 but for similar tubes along the entire row of machines such as the row depicted in Figure 5.

It is now apparent that if air under pressure flows in the manifold 19 and valve 18 is opened, suction device 15 is conditioned to draw in a yarn for discharge out of tube 16. Associated with the suction device 15 is a yarn guiding device 20 which functions to guide a yarn through the notch of the suction device while the yarn is running, whereby if the yarn so disposed is cut, the running end will be immediately entrained in the jet of air and exhausted from the tube 16.

Referring now to Figure 6, it is seen that the guide 20 is composed of a pair of inverted V-shaped members so aligned on each side of the notch in suction device 15 as to define a horizontal thread path through the notch which intercepts the axis common to the jet supplied by tube 17 and exhaust tube 16. The V-shaped members are connected together and held in place by a semi-circular metal band 20a which passes around the side of the cylindrical body opposite the notch. Band 20a may be attached to suction device 15 by any suitable means such as by soldering. The V-shaped members of guide 20 may be constructed of porcelain, metal or other material having a smooth surface. It will be noted that there is sufficient clearance between the lower edge of V-shaped members of guide 20 and the housing of suction device 15 to permit a running yarn to be easily slipped into or out of the guide 20.

The frame of the coning machine is provided with a notched tail making guide at 21 and a roller at 22, the tailing device including a cutter device 23 which is arranged to permit passage of yarn therethrough when the yarn is moving in the direction of the arrows in Figure 2, but which will instantly cut the yarn when it is running the other way. This tail making apparatus was obtained from the Universal Winding Co., Boston, Mass., and is not per se part of the present invention. Further details of the cutter device 23 are given in co-pending application Serial No. 375,401, filed August 20, 1953, reference to which is hereby made.

With the foregoing background information, it is now possible to describe how the machines are doffed according to the present invention.

During the winding-on operation, the yarn runs over the roller 12 and the dancer 13 to the button 14. When the cone is fully wound and doffing is in order, the operator approaches the machine, standing in front of it, as it appears in Figure 2, and turns valve 18 to the open position whereby suction device 15 is energized. He then rocks the traverse frame 10 in a clockwise direction moving the button 14 to the broken line position of Figure 2 whereby the thread runs onto the cone in the path shown

in broken lines in Figure 2. The operator now presses down on the running thread between the button 14 and the cone, and in this manner passes the thread through the two inverted V-shaped members of guide 20. At this stage, the yarn is still running onto the cone, but it is first passing through the thread guide 20. The operator now cuts the yarn between the guide 20 and the cone whereupon the suction device obtains control of the yarn and jets the running end into tube 16 to waste. In order to eliminate friction losses, the running yarn is slipped out from under the one side of guide 20 through which it is still running so that it passes from button 14 directly into suction device 15. At this stage, the full cone can be removed from the spindle 11 which is stopped by conventional means with which winding machines are always equipped. The operator then presses upwardly on the running yarn between the suction device and the button 14 so as to divert the yarn into guide 21 and over roller 22 whereby it automatically registers in the cutter device 23. The yarn now runs in the full line path of Figure 2. The operator next simultaneously places an empty cone on the spindle and starts the spindle. The empty cone catches the yarn at the base of the cone and causes it to be cut at 23. The running end then starts to form the tail on the base of the cone, passing over guides 24 and 21. The end between the cutter 23 and the suction device is quickly sucked in and discharged through the tube 16. When the tail is formed, the operator presses handle 21a, retracting guide 21 and releasing the yarn. He then starts the traverse and restores the traverse frame to the full line position of Figure 2. At this stage the doffing is complete and winding on may proceed until the new cone is fully formed. At any stage after the last of the waste is taken in, valve 18 can be closed. The operator then moves to the next station and repeats the operation on that machine.

Up to this point, nothing has been said of the waste that issues from the tube 16. If reference is made to Figure 1, it will be noted that the waste discharging from tube 16 enters a funnel like member 25 leading to a waste receptacle 26 on a wheeled dolly 27. As seen in Figure 4, receptacle 26 is provided with a hinged lid so waste may be removed therefrom. Above the waste receptacle, the dolly 27 is provided with vertical standards 28 and 29 having cone supports 30, 31, etc., extending from either side. Standards 28 and 29 are supported by frame 32 which is cross connected at the top as can be seen in Figure 3.

Because of the fact that the dolly 27 is ambulant and because of the straight line arrangement of successive doffing machines, an operator may accomplish successive doffing of a large number of winding machines in a most economical and efficient manner. To see how this is done, reference is made to Figure 5. In that figure, containing machines 33 to 38, inclusive, are diagrammatically shown, each machine corresponding in structure and in function to the machine shown in Figures 1 and 2. The manifold 19 runs for the full length of the group, and each machine has a tube 16 in exactly the same relative

position. This being the case, the dolly is merely pushed from stage to stage with automatic registry of the funnel member 25 at each station. It will be noted that funnel member 25 is connected to dolly 27 at such an angle that when the member 25 is aligned under a tube 16 the dolly 27 is positioned a sufficient distance away from the machine being doffed so as to not interfere with the operator's movements. Thus, without interruption, the operator may serve twenty-four machines before its waste receptacle and cone supports are full. This makes for scheduled doffing which reduces waste and at the same time keeps knot production at the desired low level.

What is claimed is:

1. The method of doffing a winding machine including a rotatable spindle and a traverse for laying up a wound yarn body thereon from a continuous supply that comprises maintaining a suction zone, changing the path of yarn travel between said body and said traverse so the yarn passes from said traverse to said suction zone and then to said body, cutting said yarn between said zone and said body whereby the succeeding portions of the yarn supplied are drawn into said suction zone and the spindle may be stopped for removal therefrom of the wound body thereon.
2. The method of threading-in a winding machine including a rotatable spindle and a traverse for laying up a wound yarn body thereon from a continuous supply that comprises maintaining a suction zone, changing the path of yarn travel between said body and said traverse so the yarn passes from said traverse to said suction zone and then to said body, cutting the yarn between said zone and said body while taking up at said suction zone the yarn continuously supplied, stopping said spindle, removing the wound body therefrom, changing the path of yarn travel between said traverse and said zone so the yarn passes from said traverse to said spindle and then to said zone, and thereafter cutting the yarn between said spindle and said suction zone.
3. In a winding machine including a spindle and a traverse the improvement that comprises a pneumatic yarn collecting device having a yarn receiving suction area and a guide for guiding a loop of thread from said traverse through said suction area to said spindle.
4. A winding machine comprising a spindle; a traverse; a pneumatic yarn drawing device having a gas supply tube, a yarn eduction notch and a discharge tube; and a yarn guide on said device defining a yarn path from said traverse through said notch to said spindle.
